(57) CLAIM

The ornamental design for an introducer, as shown and described.

DESCRIPTION

FIG. 1 is a front, top, right side perspective view of an embodiment of the introducer, showing our new design; FIG. 2 is a left side elevation view thereof; FIG. 3 is a bottom view thereof; FIG. 4 is a top view thereof; FIG. 5 is a front elevation view thereof; FIG. 6 is a rear elevation view thereof; and, FIG. 7 is a rear, top, left side perspective view thereof. The broken line portions of the figures are included to show unclaimed subject matter only and form no part of the claimed design.
